UNITED STATES PATENT OFFICE

JOHN P. McGLAUGHLIN, OF CRUGERS, NEW YORK

FILTERING DEVICE

Application filed February 3, 1930. Serial No. 425,555.

The invention relates to a filtering device adapted for connection with a fluid conducting line, by means of which the fluid passing through the line may be freed from impurities.

The primary object of the invention is to provide, in a manner as hereinafter set forth, a filtering device of the character aforesaid which may be effectively cleaned during the active use of the same without the removal of any of the parts thereof.

A further object of the invention is to provide a filtering device having the foregoing characteristics in which is employed a pair of filtering elements respectively mounted on a pair of valve members rotatably mounted within a housing and adapted to be utilized selectively for filtering the fluid passing through the line.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:

Figure 1 is a side elevation of a filtering device in accordance with this invention.

Figure 2 is a sectional plan thereof.

Figure 3 is an end elevation thereof.

Figure 4 is a vertical section thereof taken at a point indicated by the line 4-4 of Figure 2.

Figure 5 is a vertical section thereof taken at a point indicated by the line 5-5 of Figure 4.

Figure 6 is a vertical section thereof taken

at a point indicated by the line 6-6 of Figure 4.

Figure 7 is a reduced vertical section thereof taken at a point indicated by the line 7-7 of Figure 4.

Referring to the drawings in detail, the numeral 1 indicates generally a housing which includes a cylindrical body portion 2 open at its ends and having diametrically opposed wall portions adjacent each end inclining away from the axis of the body portion, such wall portions also inclining away from the ends of the body portion and providing a plurality of pockets in communication therewith. The inclined wall portions above described are designated by the numerals 3, 4, 5 and 6, and the pockets above described are designated by the numerals 7, 8, 9 and 10. The end portions of the body portion 2 are of true cylindrical forms and are designated by the numerals 11 and 12. The inclined wall portions 3 and 4 are in alignment longitudinally of the body portion and merge into an internally threaded boss 13 which provides a coupling for a pipe such as 14. The inclined wall portions 5 and 6 are in alignment longitudinally of the body portion and merge into an internally threaded boss 15 which provides a connection for a pipe such as 16.

Midway between the ends thereof, the body portion 2 is provided with a ring 17 which is formed integrally with the body portion, and the inner peripheral face of which is flush with the inner face of the body portion at the sides of the latter. The uppermost segment of the ring 17 is disposed within the pockets 9 and 10, and the lowermost segment of the ring is disposed within the pockets 7 and 8. The inner peripheral face of the ring 17 is slightly inclined away from the axis thereof, from the center of the ring toward its ends. Likewise the inner face of the body portion 2, at the sides of the latter, is inclined toward the axis of the body portion, from the ends of the

body portion to the ring. Thus it will be seen that the interior of the body portion is slightly tapered from both ends thereof toward the center.

5 Between the ring 17 and the end portion 11, the body portion 2 is formed in its sides with oppositely disposed, rectangular openings 18 and 19 which are in alignment transversely of the body portion. Between the 10 ring 17 and end portion 12, the body portion 2 is formed with a similar pair of openings 20 and 21 which are in alignment transversely of the body portion.

Supported by the ring 17 and the end portion 11 is a valve member indicated generally by the numeral 22 which includes a flanged disk 23 slidably and rotatably mounted within the end portion 11. The disk 23 is formed centrally thereof with an 15 outwardly extending, hollow stud 24 which projects beyond the outer end of the end portion 11 in spaced, concentric relation thereto. The inner face of the stud 24 is of polygonal contour to provide a receiving socket 25 for a suitable tool for rotating the valve member 22.

Formed integrally with the disk 23 are a 20 pair of oppositely disposed, spaced, arcuate plates 25, the inner ends of which are formed integrally with a flanged disk 26 slidably and rotatably mounted within the ring 17. The outer faces of the plates 25 slightly converge in a direction toward their inner ends to conform in contour with the tapered inner 25 face of the body portion 2 from the end portion 11 thereof to the ring 17. The flange of the disk 26 is normally maintained in abutment with a pair of oppositely disposed stops 27 projecting from the inner face of 30 the ring 17, by means of a coiled spring 28 which encircles the stud 24. The respective ends of the springs 28 bear against the outer face of the flanged disk 23 and the inner face of a flange 29 formed on an annulus 30 which 35 is in threaded engagement with the end portion 11. The flange 29 extends toward the stud 24 with the free edge thereof terminating adjacent the stud.

Extending between the disks 23 and 26, 40 and having its ends seating in and secured thereto, is a filtering screen 31 which is substantially in the form of a cylinder having an open side. Longitudinal marginal portions of the screen 31, at the open side of the 45 latter, are angularly offset and extend across and are secured to opposing longitudinal edge faces at one side of the opposing plates 25. The offset edge portions of the screen 31 are indicated at 32. The screen 31 is eccentrically disposed with respect to the plates 25 with the maximum space between the screen and plates located diametrically opposite the open side of the screen.

50 Supported by the ring 17 and the end portion 12 of the body portion 2 is a valve mem-

ber 33, the construction of which is identical with that of valve member 22, and therefore will not be described. For convenience in referring to the drawings, the arcuate plates of the valve member 33 are designated by the 55 numeral 34, and the filtering screen for the valve member 33 is designated by the numeral 35.

In the drawings, the valve member 33 is shown adjusted with respect to the housing in a manner to close the pockets 8 and 10 from the interior of the body portion 2 by means of the arcuate plates 34, and to establish communication between the openings 20 and 21, between the plates 34. The open side of the screen 35 is arranged at the opening 20 whereby only one thickness of the wall of the screen is interposed between the openings 20 and 21.

55 The valve member 22 is adjusted with respect to the housing in a manner to close the openings 18 and 19 by means of the plates 25, and to establish communication between the pockets 7 and 9 between the plates 25. The open side of the screen 31 is arranged at the pocket 7 whereby only one thickness of the wall of the screen is interposed between the pockets 7 and 9. In the arrangement illustrated, the pipe 14 is the inlet pipe, and the pipe 16 is the outlet pipe. With the valve members arranged as shown, a fluid entering 60 the housing from the pipe 14 will be passed through the pocket 7, filter screen 31, and pocket 9 to the outlet pipe 16, and any impurities separated from the fluid by the screen 31 will be deposited within the latter. Owing to the position of the plates 34 of the valve member 33, the sole passage between the pipes 14 and 16 is through the screen 31. With the valve member 33 in the position illustrated, 65 the screen 35 is in proper position to have flushed therefrom any impurities which may have collected therein during its utilization to establish communication between the pockets 8 and 10. Obviously, by directing a fluid stream through the opening 21, any foreign matter within the screen 35 will be washed out of the housing through the opening 20. When it becomes necessary to clean the screen 70 through which the fluid is being filtered, this may be readily accomplished without cutting off the flow between the pipes 14 and 16 merely by reversing the position of the valve members.

75 It is thought that the many advantages of a filtering device in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

80 What I claim is:

1. In a filtering device for interposition between a pair of sections of a fluid conducting line, a cylindrical housing disposed transversely with respect to said section and having its body formed with a pair of diametrically opposed oppositely extending outwardly projecting hollow tapered portions for connection centrally thereof to the pipe sections, a ring within, integral with and aligning with the vertical medians of said tapered portions and providing in connection with the inner ends of the latter two spaced pairs of spaced aligning openings, said housing formed with an opening at each 15 end aligning with said ring, a pair of oppositely disposed rotatable valves, each interposed between the openings of a pair of openings and consisting of a pair of spaced disks having oppositely disposed flanges seating 20 in an end opening and the ring and oppositely disposed arcuate spaced plates connecting said disks together and in connection with the latter providing a passage through the valve, and a filter member in the form of a 25 cylinder open at one side and having the longitudinal marginal portions angularly disposed, said cylinder arranged between, disposed eccentrically with respect to and having its ends seated in said disks, the said 30 marginal portions of said member opposing and secured to opposed lengthwise end edges at one side of said plates.

2. In a filtering device, a rotatable combined valve and filtering unit therefor, the 35 valvular part of said unit consisting of a pair of opposed spaced disks having oppositely disposed supporting flanges therefor projecting from one face thereof and oppositely disposed, opposed arcuate spaced plates integral with the other face of said disks for 40 connecting them together and in connection with the latter providing a passage through said part, and said filtering part of said unit consisting of a reticulated member in the 45 form of a cylinder open at one side and having the longitudinal marginal portions thereof angularly disposed, said cylinder disposed eccentrically to and having its ends seated in said disks and its longitudinal marginal portions opposing and secured to opposed longitudinal edges at one side of said plates. 50

3. In a filtering device, a rotatable combined valve and filtering unit therefor, the valvular part of said unit consisting of a 55 pair of opposed spaced disks having oppositely disposed supporting flanges therefor projecting from one face thereof and oppositely disposed, opposed arcuate spaced plates integral with the other face of said disks for 60 connecting them together and in connection with the latter providing a passage through said part, said filtering part of said unit consisting of a reticulated member in the form of a cylinder open at one side and having the longitudinal marginal portions thereof 65

angularly disposed, said cylinder disposed eccentrically to and having its ends seated in said disks and its longitudinal marginal portions opposing and secured to opposed longitudinal edges at one side of said plates, 70 and one of said disks on that face thereof provided with its supporting flange having axially thereof and integral therewith an outwardly directed polygonal socket forming member to receive means to rotate the 75 unit.

In testimony whereof, I affix my signature hereto.

JOHN P. McGLAUGHLIN.
